UNITED STATES PATENT OFFICE.

HENRY D. LEFEBVRE, OF ALPENA, MICHIGAN.

LACING AND LACE-FASTENER.

1,152,422.

Specification of Letters Patent. Patented Sept. 7, 1915.

Application filed February 8, 1915. Serial No. 5,814.

To all whom it may concern:

Be it known that I, HENRY D. LEFEBVRE, a citizen of the United States, residing at Alpna, in the county of Alpna and State 5 of Michigan, have invented certain new and useful Improvements in Lacings and Lace-Fasteners, of which the following is a specification.

The present invention relates to certain 10 new and useful improvements in lacing means, and has for its object to provide a novel construction whereby the lacing operation may be quickly and perfectly accomplished without loss of time and the lacing 15 terminals either knotted in the usual manner or brought into engagement with a spring clip at the option of the user.

Further objects of the invention are to 20 provide a lacing means and terminal which is simple and inexpensive in its construction, which admits of the two opposed edges or elements being perfectly connected in the desired manner without loss of time, which can be quickly manipulated with but one 25 hand, and which can be used with equal facility upon shoes, overshoes, gloves and the like.

With these and other objects in view, the 30 invention consists in certain novel combinations and arrangements of the parts as will more fully appear as the description proceeds, the novel features thereof being pointed out in the appended claims.

For a full understanding of the invention, reference is to be had to the following 35 description and accompanying drawing, in which:—

Figure 1 is a perspective view of a shoe 40 provided at the front thereof with a lacing device constructed in accordance with the invention. Fig. 2 is a perspective view of a shoe provided at one side thereof with a lacing arrangement constructed in accordance with the invention, the shoe being 45 shown as laced and the lacing terminals connected by a knot in the usual manner. Fig. 3 is an enlarged detail view of the upper portion of a shoe constructed to be laced in accordance with the invention, the lacing 50 terminals being connected by the usual knot. Fig. 4 is a similar view showing the lacing terminals as engaged by the spring clip. Fig. 5 is a detail perspective view of the 55 combined spring clip and lacing hook. Fig. 6 is an edge view of the same showing it as

applied to a thickness of material, said thickness of material appearing in section.

Corresponding and like parts are referred to in the following description and indicated in all the views of the drawings by the same 60 reference characters.

For the purpose of illustration the invention has been shown upon the drawing as used in connection with a shoe, although it will be understood that it is equally well 65 adapted for use upon gloves, leggings, and like articles.

In Fig. 1 the shoe 1 is shown as formed with an upper which opens at the front, while in Fig. 2 the shoe 2 is shown as formed with 70 an upper which opens at one side. The manner of applying the lacing to the shoe is identical in each case, so that the same description will apply to both forms of shoe. One of the edges or elements 3 to be 75 connected is provided with a series of lacing hooks 4 of the conventional construction and eyelets 5 at the ends of the series of lacing hooks. The opposite edge or element 6 to be connected is provided with a series of lac- 80 ing hooks 7 which have a staggered relation with respect to the opposed lacing hooks 4. Said opposite edge 6 is also provided at one end of the series of lacing hooks with a terminal clip C which has a peculiar construction so that the ends of the lace can either 85 be knotted or engaged by the terminal clip at the option of the user. This terminal clip C may be economically constructed from a a single piece of sheet material. A 90

flat base 8 has a pair of parallel slits cut in each end thereof, thereby providing an intermediate tongue and a pair of side prongs at each end of the base. The side prongs 95 may be suitably sharpened and bent rearwardly as indicated at 9, so as to be employed in the usual manner for securing the terminal clip to the thickness of leather or other material. The intermediate tongue at one end of the base plate 8 is comparatively 100 short and is bent outwardly to provide a rigid hook 10. The intermediate tongue at the opposite end of the base plate is comparatively long and is deflected outwardly so as to provide a yielding arm 11 which is 105 adapted to coöperate with the base plate to grip a lace or like member which may be forcibly drawn under the same. The free end of the spring clamping arm 11 is re- 110 turned at 12 so as to provide a rounded nose

for directing a lace under the clamping arm, and also provide a lacing hook at one end of the series of lacing hooks 7 upon the edge or element 6 to be connected.

5 A preferred manner of using a lace in connection with the lacing hooks and spring terminal clip is illustrated by the drawings. An intermediate portion of the lace 14 is threaded twice through the lower eye 5 of 10 the edge 3. One end of the lace 14 is carried upwardly on the inside of the shoe and passed through the upper eye 5, while the opposite end of the lace is adapted to be threaded back and forth in a zigzag manner 15 through the two series of lacing hooks 4 and 7 for the purpose of connecting the opposed edges 3 and 6 in the desired manner. The extremity of this end of the lace 14 may either be passed around the lacing hook member 12 of the terminal clip and connected to the opposite extremity of the lace by 20 means of a knot 15 in the usual manner, or the two extremities of the lace may be placed together, first drawn around the fixed hook member 10 at the rear end of the terminal clip and then drawn around the spring clamping arm 11 so as to be engaged thereby, as indicated by Fig. 4. It is entirely optional with the user whether he will connect 25 the extremities of the lace by a knot, as illustrated by Figs. 2 and 3, or whether he will merely draw them into an operative engagement with the spring terminal clip, as illustrated by Fig. 4. The lacing can be very 30 quickly accomplished with a single hand, and a perfect connection is provided between the opposed edges or elements to be joined.

Having thus described the invention, what I claim as new and desire to secure 40 by Letters Patent, is:—

Copies of this patent may be obtained for five cents each, by addressing the "Commissioner of Patents, Washington, D. C."

1. A lacing terminal clip formed from a single piece of sheet material and including a plate having a rigid hooked arm at one end thereof and an opposed spring clamping arm at the opposite end thereof, said rigid hooked 45 arm and spring clamping arm projecting in opposite directions and the extremity of the spring clamping arm being returned outwardly to provide a lacing hook carried by the clamping arm and extending in an opposite direction thereto.

2. A lacing terminal clip formed from a single piece of sheet material and including a plate having a pair of parallel slits in each end thereof, said slits providing an intermediate tongue and a pair of side prongs at each end of the plate, and the corresponding tongues and side prongs being in alignment with each other, the side prongs being sharpened and bent rearwardly and one of the intermediate tongues being comparatively short and bent outwardly to provide a rigid hooked arm while the opposite intermediate tongue is comparatively long and is deflected outwardly to provide a spring clamping 65 arm adapted to coöperate with the plate to grasp a lacing, the rigid hooked arm and the spring clamping arm projecting in opposite directions from the plate and the extremity of the clamping arm being returned to provide a lacing hook which is carried by the spring clamping arm and projects in the opposite direction thereto.

In testimony whereof I affix my signature in presence of two witnesses.

HENRY D. LEFEBVRE.
